(57) **CLAIM**

The ornamental design for a light fixture with adjustable track lighting, as shown and described.

DESCRIPTION

FIG. 1 is a bottom perspective view of the light fixture with adjustable track lighting;

FIG. 2 is a bottom side view of the light fixture, the opposing side being a mirror image thereof; and,

FIG. 3 is one side view of the light fixture, the other side views being symmetrical images thereof.

The broken lines showing of environmental structure are for illustrative purposes only and form no part of the claimed design.
